(57) **CLAIM**

The ornamental design for a multi-hole absorption device for industrial robot arm, as shown and described.

DESCRIPTION

FIG. 1 is a front view of a multi-hole absorption device for industrial robot arm in accordance with Embodiment 1 of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a front view of an industrial robot arm in accordance with Embodiment 2 of the present design;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a first perspective view thereof; and,

FIG. 16 is a second perspective view thereof.

The broken lines shown in the drawings represent portions of the multi-hole absorption device for industrial robot arm that form no part of the claimed design.

1 Claim, 9 Drawing Sheets
